UNITED STATES PATENT OFFICE.

MARTIN NYSTROM, OF CHICAGO, ILLINOIS, ASSIGNOR TO THE BRUNSWICK-BALKE-COLLENDER COMPANY, OF CHICAGO, ILLINOIS, A CORPORATION OF DELAWARE.

GOVERNOR MECHANISM FOR TALKING MACHINES.

1,403,344.

Specification of Letters Patent. Patented Jan. 10, 1922.

Application filed August 16, 1919. Serial No. 317,882.

To all whom it may concern:

Be it known that I, MARTIN NYSTROM, a citizen of the United States, residing at Chicago, in the county of Cook and State of Illinois, have invented certain new and useful Improvements in Governor Mechanism for Talking Machines, of which the following is a specification.

This application is a continuation in part 10 of my application for Letters Patent No. 1,361,174, patented December 7, 1920.

The object of this invention is to provide a sensitive and efficient governor mechanism for talking machine spring motors which is 15 simple in construction, easy to adjust and positive in operation.

Another object is to pivotally mount a pair of braking pads for controlling the speed of the motor so that they will automatically adjust themselves for unevenness in wear or position and constantly cooperate with maximum efficiency to perform their intended function.

In the accompanying drawing illustrating 25 a preferred embodiment of the invention

Fig. 1 is an elevation, partly broken away and in section, of a motor embodying the invention:

Fig. 2 illustrates the governor mechanism 30 in elevation and in its proper relation to the motor parts;

Fig. 3 is a sectional view on the line 3—3 of Fig. 2; and

Fig. 4 is a perspective view of the gov- 35 ernor lever.

Referring to the drawings, 8 is one end member and 10 is the top member of a suitable frame in which is mounted a spindle 11 which projects up through openings in 40 the top member 10 and the top plate or motor board 13 to carry the record table. The spindle has a pinion 16 which meshes with a spiral gear 17 on drive shaft 18, the latter having a worm 18' located between and 45 meshing with driving gears 20, 20' suitably supported in the frame and driven by power springs in the barrels 23. The springs are wound by operating the winding shaft 24 through connections not shown.

50 A brake device comprising a pad 25 carried by arm 26 on brake rod 27 is operated by a spindle 28 which in turn is operated by devices on the top plate or motor board as more fully described in my companion

application for Letters Patent No. 1,361,176, 55 patented December 7, 1920.

A governor shaft 32 is supported in lugs 33 on the end member 8 of the frame and is provided with a worm 34 which is driven by a worm gear 35 on the spindle. The 60 governor comprises a sleeve 36 mounted on the shaft 32 and carrying a drum 37 at one end and a collar 38 at the other end thereof.

A plurality of governor springs 39 are fastened at one end to the collar 38 and at the 65 other end to a collar 39' fast on the governor shaft, the springs extending through openings provided therefor in the drum. These springs carry weights 40 which are conveniently located for operation within the 70 drum. A speed control lever 41 is pivotally mounted between its ends on the frame at 42. One arm of this lever projects downward adjacent the drum and carries a fork 43 pivoted at 43' on the lever. This fork 75 has two projecting fingers 44 carrying pads 45 on opposite sides of the governor shaft to engage the drum. By thus pivoting the fork on the lever I provide at all times for

engagement of both pads with the drum 80 since it will be readily understood that the fork will adjust itself to any unequal wear or other inequalities in the pads. The other arm of the lever 41 projects outwardly and is split to provide the two fingers 46, 46' 85

which embrace the lower end of an adjusting device comprising a pin 47 projecting upwardly through the top member of the frame and the top plate or motor board and provided with a knurled head 48 and an indicating point 48'. Spring 49 on the pin bears constantly upon the lever 41 to hold the pin in adjusted position. The lower end of the adjusting pin 47 is provided with a helical groove or thread 50 in which one 90 finger 46 travels, this finger being bent to a proper position to fit in the groove. The other finger 46' travels free from the groove against the pin and holds finger 46 in the 95 groove.

100 By turning the knurled head 48, the lever 41 may be swung on its pivot to carry the pads 45 into position relative to the drum to control the speed thereof. Thus, by turning the head 48 to move the pads farther away from the drum, the motor will be permitted to operate at a higher rate of speed and conversely by moving the pads nearer to the 105

drum the speed of operation of the motor will be reduced.

My invention provides a governor mechanism which can be adjusted to a fine degree, and which is sensitive in operation and positive in action. By mounting the pads on a pivoted fork to engage the drum on opposite sides of the governor shaft I provide an efficient controlling means which will automatically adjust itself to inequalities of wear or otherwise for efficient operation at all times.

I am aware that changes in the form and proportion of parts and in the details of construction may be made without departing from the spirit or sacrificing any of the advantages of the invention and I therefore reserve the right to make all such changes as fairly fall within the scope of the following claims.

I claim:

1. The combination of a governor shaft, a governor mounted thereon and comprising a drum, a control lever carrying means at one end to engage said drum, a rotatable adjusting pin having a helical groove therein, and means at the other end of said lever to engage said groove.

2. The combination of a governor shaft, a governor mounted thereon and comprising a drum, a control lever carrying means at

one end to engage said drum, a rotatable threaded pin, a finger on the other end of said lever bent to engage said threaded pin, and means for holding said finger against said threaded pin.

3. The combination of a governor shaft, a governor mounted thereon and comprising a drum, a control lever carrying means at one end to engage said drum, a rotatable pin having a helical groove therein, and two fingers on the other end of said lever and embracing said pin, one finger being bent and operating in said groove, and the other finger engaging the side of the pin to hold the bent finger in the groove.

4. The combination of a governor shaft, a governor mounted thereon and comprising a drum, a control lever carrying means at one end to engage said drum, a rotatable pin having a helical groove at one end and a head at the other end, two fingers on the other end of said lever, one finger being bent to engage the groove and the other finger engaging the side of the pin to hold the bent finger in the groove, and a spring on the pin engaging the fingers to hold the pin and lever in adjusted position.

MARTIN NYSTROM.
